UNITED STATES PATENT OFFICE.

JAMES WEST, OF ST. LOUIS, MISSOURI, ASSIGNOR TO THE SAMUEL CUPPLES ENVELOPE COMPANY, OF SAME PLACE.

ENVELOP.

SPECIFICATION forming part of Letters Patent No. 653,599, dated July 10, 1900.

Application filed March 22, 1900. Serial No. 9,703. (No model.)

To all whom it may concern:

Be it known that I, JAMES WEST, a citizen of the United States, residing at the city of St. Louis, in the State of Missouri, have invented certain new and useful Improvements in Envelops, of which the following is a full, clear, and exact description, reference being had to the accompanying drawings, forming part of this specification.

10 My present invention relates to an envelop for use in sending "open matter" through the mails, the object of my invention being to make such an envelop that will have the appearance and possess practically the security 15 to the contents of a sealed envelop.

My invention consists in features of novelty hereinafter fully described, and pointed out in the claims.

Figure I is an inside view of a gummed 20 blank of which my envelop is made. Fig. II is a like view with the end folds of the envelop turned in. Fig. III is a view of the envelop completely folded and ready for use. Fig. IV is a view of the envelop after the sealing-flap 25 has been closed and showing how the end fold may be turned to permit the contents of the envelop to be removed for inspection should such inspection be desired. Fig. V is a perspective view of the envelop, showing the 30 back at the open end of the envelop disconnected from the gummed lip of the fold of this end of the envelop. Fig. VI is a longitudinal section of the envelop, showing how the open end may be spread apart to obtain 35 a view of the contents of the envelop. Fig. VII is a like view showing the envelop in its normal position.

1 represents the back, and 2 the front, of the envelop, from the latter of which extends 40 the ordinary sealing-flap 3, which is gummed, as shown at 4.

At one end of the envelop is a fold 5, intended to be folded on the dotted line 6 and which when folded presents a gummed surface, as shown in Fig. II, so that when the back and front of the envelop are folded together on the line 7 this end of the envelop will be sealed and closed. Other means, however, may be employed for sealing or closing 45 this end of the envelop, as my present invention relates to the manner of forming the other

end of the envelop. At the last-mentioned end of the envelop there is a fold 8, adapted to be folded on the line 9, and half of which, preferably that portion that extends from the back of the envelop, is gummed, as shown in Fig. I, so that when the fold is folded over on the line 9 the gummed part will be caused to adhere to the body of the envelop. The other half of this fold is not gummed, so that when the fold is folded over it will not adhere to the body of the envelop. This fold of the envelop has a projecting tongue 11, gummed, as shown in Figs. I and II, so that when the back and front of the envelop are folded together, as stated, this tongue can be sealed down onto the back, as shown in Fig. III, and the upper corner of the back of the envelop is thus held to the front of the envelop. The adjacent faces of the fold 8 are not gummed 60 or stuck together, so that this end of the envelop is left open.

When a circular or other matter 12 is placed in the envelop, the flap 3 is sealed down, and one end of the circular fits between the front 75 of the envelop and the fold 8, as shown in Figs. V, VI, and VII, so that there is no danger of its falling out of the open end of the envelop. If it be desired to get a view of the contents of the envelop, its open end can be 80 spread apart, as shown in Fig. VI, and when released will close again, as shown in Fig. VII.

Should the postal authorities desire to remove the contents of the envelop for examination, this may be done by turning outwardly 85 the loose part of the fold 8, as shown in Fig. IV, and to facilitate this I perforate the fold at 13, so that it can be torn readily on straight lines as it is being turned out. After the contents have been examined and returned the 90 fold is tucked back into the envelop, where it will remain as if it had not been removed.

It will be observed that when the circular or other matter is placed in the envelop and the flap 3 is sealed down the article has the 95 appearance of a sealed letter, while at the same time its contents can be readily examined and are retained in place and are in no danger of falling out of the envelop.

I claim as my invention—

1. An envelop comprising front and back portions, sealed together at one end, a top

gummed flap, and a wide fold on the other end of the envelop, extending the width thereof, folded in between the front and back portions, one half of the same being gummed down while the other half is free to be pulled out.

2. An envelop having a front and back portion, closed at one end and having a gummed flap; the other end of said envelop being formed with a fold, one portion of which is adapted to be sealed to the back of the envelop and the other portion of which is folded against the front of the envelop and left free so that the contents can fit behind the same, substantially as described.

3. An envelop consisting of a front and back portion closed at one end and having a flap adapted to be sealed to the back portion; said envelop having a fold at the end thereof that is not closed, said fold having a portion adapted to be sealed down against the back portion of the envelop, substantially as described.

4. An envelop consisting of a front and back portion closed at one end and having a flap adapted to be sealed against the back portion, and having also a fold, one portion of which

is sealed to the back of the envelop while the remaining portion is left free and folded against the front of the envelop; and a projection from the fold adapted to be sealed to the back of the envelop, substantially as set forth.

5. An envelop comprising a front and back portion secured together at one end, a top gummed flap, a wide fold on the other end of the envelop extending the width thereof, and a projection extending from the top of said fold, said fold having lines of perforations to permit part thereof to be turned out to allow the removal of the contents of the envelop.

6. An envelop consisting of a front and back portion, with a flap on the front portion adapted to be sealed to the back portion, and a wide fold on one end of the envelop extending the width thereof, and the adjacent faces of which are left unattached, substantially as and for the purpose set forth.

JAMES WEST.
